STICK SHIFT FOR BICYCLE

Stanley R. Jameson, Chicago, and Anton J. Panzica, Hinsdale, Ill., assignors to Schwinn Bicycle Company, a corporation of Illinois

Filed Feb. 1, 1966, Ser. No. 854

Term of patent 14 years

(Cl. D90—1)

FIGURE 1 is a side elevational view of a stick shift for bicycle embodying the features of our invention illustrated as mounted on a bicycle with portions of the latter shown in broken lines for illustrative purposes only;

FIG. 2 is a side elevation similar to FIG. 1 on a larger scale;

FIG. 3 is a front elevational view as seen from the right side of FIG. 2;

FIG. 4 is a side elevational view as seen from the opposite side of that shown in FIG. 2;

FIG. 5 is a rear elevation, as seen from the left side of FIGS. 1 and 2, with the upper portion of the stick shift broken away merely for convenience of illustration; and

FIG. 6 is a vertical detail sectional view through the annular cover member shown at the right side of FIG. 5.

In view of the prior art, the characteristic features of our design reside in the overall appearance, in association with the lever and knob shown, resulting from the pointer extending from the lever over the base of the housing

together with the specific configuration of the cover plate, as best seen in FIGS. 2, 5, and 6.

We claim:

The ornamental design for a stick shift for bicycle, as shown and described.
